Samuel S. Schiffer, New York, N. Y.

Application May 2, 1951, Serial No. 15,043

Term of patent 14 years

(Cl. D33—2)

To all whom it may concern:

Be it known that I, Samuel S. Schiffer, a citizen of the United States of America, residing at New York, State of New York, have invented a new, original, and ornamental Design for Rack, of which the following is a specification, reference being had to the accompanying drawing, forming a part hereof, and in which

Fig. 1 is a perspective view of a rack, showing my new design.

Fig. 2 is a rear elevational view of the rack shown in Fig. 1; and

Fig. 3 is a side view of the rack looking to the left in Fig. 1.

I claim:

The ornamental design for a rack, as shown.
SAMUEL S. SCHIFFER.
